UNITED STATES PATENT OFFICE.

ELIJAH MCCOY, OF DETROIT, MICHIGAN, ASSIGNOR TO YPSILANTI LUBRICATOR COMPANY, OF YPSILANTI, MICHIGAN, A CORPORATION OF MICHIGAN.

LUBRICATOR.

1,031,948.

Specification of Letters Patent.

Patented July 9, 1912.

Application filed February 19, 1906. Serial No. 302,675.

To all whom it may concern:

Be it known that I, ELIJAH McCoy, a citizen of the United States of America, residing at Detroit, in the county of Wayne and 5 State of Michigan, have invented certain new and useful Improvements in Lubricators, of which the following is a specification, reference being had therein to the accompanying drawings.

10 The invention relates to lubricators of that type particularly adapted for use on locomotives, and for feeding the oil into the cylinders against high pressure steam.

15 The invention consists in certain features of construction as will be more fully herein-after set forth.

In the drawings, Figure 1 is a diagrammatic side elevation of a locomotive to which the lubricator is attached; Fig. 2 is 20 an end elevation thereof; Fig. 3 is a diagrammatic perspective view, illustrating the various pipe connections of the lubricator; Fig. 4 is a top plan view; Fig. 5 is an enlarged horizontal section of a portion of 25 Fig. 4; Fig. 6 is a sectional elevation of the lubricator, viewed as in Fig. 2; Fig. 7 is a section through the upper portion of the condenser; Fig. 8 is a section through the conduit for replenishing water to the sight- 30 feed and supplying steam to the heater; and Fig. 9 is a cross section through a form of locomotive cylinder and steam chest, illustrating the pipe connections thereto.

A is an oil cup, B is a condenser connected 35 with said cup for feeding the oil therefrom by hydrostatic pressure, and C is a pump for receiving the oil from said cup and mechanically propelling it to the parts to be lubricated. These parts are preferably as- 40 sembled in fixed relation to each other and are adapted to be secured to a locomotive boiler D, in convenient position, as by means of the bracket E.

45 F F' are the tallow pipes through which the oil is forced by the pump C and which lead to the cylinders G of the locomotive.

The steam for supplying the condenser B and for operating the pump C is supplied 50 from any suitable source, as for instance the steam box H on the locomotive boiler, to which all the various steam conduits are usually connected.

I is a valve connected to the box H controlling 55 the steam supply to two separate conduits J, J', the one leading to the top of

the condenser B, and the other connecting to the steam cylinder C' of the pump C. These conduits are preferably arranged to drain backward into the steam box, and the conduit J' is arranged at a higher level than 60 the conduit J, in order that any condensation in the pipes may pass to the condenser B, rather than to the steam cylinder C'. All of the steam employed in operating or controlling the lubricator is supplied 65 through one or the other of the conduits J, J' and is controlled by the single valve I, so that when the latter is closed, the whole apparatus is thrown out of action.

In addition to supplying oil to the cylinders of the locomotive, the lubricator is also provided with an attachment for lubricating the air brake cylinder; and further with a conduit by which the cylinder of the operating pump C may also be lubricated. The 70 various parts of the apparatus are prefer- 75 ably assembled in the relation illustrated in Figs. 1, 2, and 3, in which the oil cup A is directly connected to the supporting bracket E, and a laterally projecting arm E' from 80 said bracket supports the oil pump C at one side of the cup. The condenser B is ar- ranged in rear of the cup, and two sight feeds K, K', the one for the locomotive cyl- 85 inders and the other for the air brake, are arranged on opposite sides of the cup A, as shown.

Hydrostatic feed.—All the various conduits for receiving oil are supplied in the first place from the cup A by hydrostatic 90 feed. To this end, the condenser B is connected to a pipe a leading downward through the cup A into a central well b at the bottom thereof, the latter being prefer- 95 ably formed in a detachable plug b'.

c and d are pipes leading from the upper portion of the chamber within the oil cup, downward and outward respectively to the sight feeds K, K'. e is a feed pipe, connected with a conduit e' which forms a by- 100 pass around the sight feed K and connects with the discharge conduit therefrom, being designed for use in emergency, as when the glass of the sight feed breaks. To all of 105 these oil pipes c, d and e, oil is fed by the hydrostatic pressure of the water column in the condenser B, as is usual in lubricators of this type.

After passing into the tallow pipes F, F', the feeding of the oil is controlled by auto- 110

UNITED STATES PATENT OFFICE.

ELIJAH MCCOY, OF DETROIT, MICHIGAN, ASSIGNOR TO YPSILANTI LUBRICATOR COMPANY, OF YPSILANTI, MICHIGAN, A CORPORATION OF MICHIGAN.

LUBRICATOR.

1,031,948.

Specification of Letters Patent.

Patented July 9, 1912.

Application filed February 19, 1906. Serial No. 302,675.

To all whom it may concern:

Be it known that I, ELIJAH MCCOY, a citizen of the United States of America, residing at Detroit, in the county of Wayne and 5 State of Michigan, have invented certain new and useful Improvements in Lubricators, of which the following is a specification, reference being had therein to the accompanying drawings.

10 The invention relates to lubricators of that type particularly adapted for use on locomotives, and for feeding the oil into the cylinders against high pressure steam.

15 The invention consists in certain features of construction as will be more fully herein-after set forth.

In the drawings, Figure 1 is a diagrammatic side elevation of a locomotive to which the lubricator is attached; Fig. 2 is 20 an end elevation thereof; Fig. 3 is a diagrammatic perspective view, illustrating the various pipe connections of the lubricator; Fig. 4 is a top plan view; Fig. 5 is an enlarged horizontal section of a portion of 25 Fig. 4; Fig. 6 is a sectional elevation of the lubricator, viewed as in Fig. 2; Fig. 7 is a section through the upper portion of the condenser; Fig. 8 is a section through the conduit for replenishing water to the sight- 30 feed and supplying steam to the heater; and Fig. 9 is a cross section through a form of locomotive cylinder and steam chest, illustrating the pipe connections thereto.

A is an oil cup, B is a condenser connected 35 with said cup for feeding the oil therefrom by hydrostatic pressure, and C is a pump for receiving the oil from said cup and mechanically propelling it to the parts to be lubricated. These parts are preferably assembled in fixed relation to each other and 40 are adapted to be secured to a locomotive boiler D, in convenient position, as by means of the bracket E.

45 F F' are the tallow pipes through which the oil is forced by the pump C and which lead to the cylinders G of the locomotive.

The steam for supplying the condenser B and for operating the pump C is supplied 50 from any suitable source, as for instance the steam box H on the locomotive boiler, to which all the various steam conduits are usually connected.

I is a valve connected to the box H controlling the steam supply to two separate 55 conduits J, J', the one leading to the top of

the condenser B, and the other connecting to the steam cylinder C' of the pump C. These conduits are preferably arranged to drain backward into the steam box, and the conduit J' is arranged at a higher level than 60 the conduit J, in order that any condensation in the pipes may pass to the condenser B, rather than to the steam cylinder C'. All of the steam employed in operating or controlling the lubricator is supplied 65 through one or the other of the conduits J, J' and is controlled by the single valve I, so that when the latter is closed, the whole apparatus is thrown out of action.

In addition to supplying oil to the cylinders of the locomotive, the lubricator is also provided with an attachment for lubricating the air brake cylinder; and further with a conduit by which the cylinder of the operating pump C may also be lubricated. The 70 various parts of the apparatus are preferably assembled in the relation illustrated in Figs. 1, 2, and 3, in which the oil cup A is directly connected to the supporting bracket E, and a laterally projecting arm E' from 75 said bracket supports the oil pump C at one side of the cup. The condenser B is arranged in rear of the cup, and two sight feeds K, K', the one for the locomotive cylinders and the other for the air brake, are 80 arranged on opposite sides of the cup A, as shown.

Hydrostatic feed.—All the various conduits for receiving oil are supplied in the first place from the cup A by hydrostatic 90 feed. To this end, the condenser B is connected to a pipe a leading downward through the cup A into a central well b at the bottom thereof, the latter being preferably formed in a detachable plug b'.

c and d are pipes leading from the upper portion of the chamber within the oil cup, downward and outward respectively to the sight feeds K, K'. e is a feed pipe, connected with a conduit e' which forms a bypass around the sight feed K and connects with the discharge conduit therefrom, being designed for use in emergency, as when the glass of the sight feed breaks. To all of these oil pipes c, d and e, oil is fed by the 100 hydrostatic pressure of the water column in the condenser B, as is usual in lubricators of 105 this type.

After passing into the tallow pipes F, F', the feeding of the oil is controlled by auto- 110

matic valves F^2 , the opening of which is resisted by a steam pressure equal to that in the steam cylinder of the pump C . The specific construction of these valves F^2 forms 5 no part of the present invention, and is therefore not illustrated. In function, the valves F^2 act as governors for securing the uniform operation of the pump under varying steam pressures, and also under varying 10 back pressure pulsations in the locomotive cylinders. The steam operating upon the valves F^2 is supplied through a conduit P preferably attaching to the top of the condenser B and branching at P' to lead to the 15 two valves. As shown, the pipe P is mechanically tied to the conduit J' , which supplies steam to the cylinder of the pump C by a yoke P^2 , and this fitting, as illustrated in Fig. 4, is preferably formed integral 20 with an elbow P^3 , forming a bend in the pipe P , but the pipes P and J' have no steam connection through this fitting.

The oil supplied to the cylinder i of the pump C is controlled by the sight feed K through a valve K^2 controlling the oil discharge nozzle K^3 connecting the pipe c . After passing through the water in the transparent tube K^4 , the oil is delivered into a conduit K^5 , leading to the pump C . The 30 by-pass e' also connects with the conduit K^5 and this is controlled by the valve e^2 which is normally closed, so that all of the oil fed to the pump passes by way of the sight-feed.

Heater and water replenisher for sight feed.—To maintain the proper feeding of the oil, it is desirable to prevent it from becoming too cold, and to this end a heater is provided, which may be regulated to keep the oil at the desired temperature. It is 40 also necessary to provide means for replenishing the water in the transparent tube K^4 of the sight feed. I have therefore provided a steam conduit L , which preferably leads from the top of the condenser B and 45 furnishes steam both for the heater and for replenishing the sight feed, the construction being as follows:— L' is the fitting to which the upper end of the transparent tube K^4 of the sight feed is attached. This fitting is provided with a nipple q engaging a threaded aperture in the cup A , and L^2 is a 50 radiator tube connected into this nipple and extending across the cup near the upper end thereof. The tube L^2 communicates through 55 a passage q' in the fitting L' with a laterally projecting arm q^2 of the fitting, in which is arranged the valve L^3 . The conduit L is also connected to this arm q^2 , and the passage of steam through the conduit is 60 controlled by valve L^3 . The valve is, however, provided with a restricted port r , which is open when the valve is seated, so that there is a constant communication through the port between the conduit L and 65 the radiator tube L^2 . Within the conduit L

is arranged a further restriction, which operates to limit the amount of steam fed, and also to prevent the clogging of the ports by sediment carried by the steam. As shown in Figs. 7, 8, two separate restrictions are 70 placed in the conduit L . The first of these is the nozzle r' , which is secured within a nipple r^2 at the upper end of the condenser, and has its inner end tapered to a point and provided with a restricted port r^3 . The 75 nozzle r' is preferably secured by a screw threaded engagement in the nipple r^2 , and in case of clogging at any time, may be readily removed for cleaning. The conduit L is connected to the nipple r^2 by a detachable coupling r^4 to permit of quickly disengaging the conduit. At the lower end of the conduit L is a second nozzle s , which is preferably secured to the nipple s' upon the arm q^2 of the fitting L' . The upper end 80 of this nozzle is also tapered to a point and is provided with the restricted port s^2 . Both the nozzles r' and s are of smaller external diameter than the conduits in which they are placed, so as to provide a well or chamber for the collection of sediment. Thus, the steam which enters the upper part of the condenser through the conduit J is obliged to pass first through the restricted port r^3 into the nozzle r' , and after passing 85 through the conduit L to again pass through the restricted port s^2 into the nozzle s before it finally enters the fitting L' . In this fitting, when the valve L^3 is seated the passage of the steam is again restricted by the 90 port r . Thus, the carrying of sediment into the fitting L' is effectually prevented, and when the valve L^3 is closed, the restriction is so great as to prevent the passage of more than the water of condensation into the fitting L' . The fitting L' is further provided with a passage q^3 , which connects the passage q' with the conduit K^5 leading to the oil cylinder of the pump. q^3 is the port in the fitting L' connecting the oil space therein 95 above the transparent tube K^4 with the conduit K^5 , and this port q^4 is arranged below the level of the port q^3 , so that the water of condensation passing through the latter into the conduit K^5 will drain backward into the transparent tube K^4 .

It will be understood from the above description that water is constantly supplied to the tube K^4 from condensation in the conduit L and its connections; and further than this water is filtered from impurities by passing through the various restrictions in the conduit L and valve L^3 . Should any minute particles of sediment pass through these restrictions, they are prevented from lodging in the fitting L' by making the port q^3 larger than the restricted ports before mentioned. Where it is desired to supply heat as well as water of condensation, the valve L^3 is opened to provide a freer pas- 100

sage, with the consequence that hot water or steam is supplied from the conduit L to the radiator tube L² and will supply the necessary heat to the oil.

5 In lubricators of the type where the oil is propelled beyond the sight-feed by a jet of steam, the latter will always maintain the oil at relatively high temperature. With my construction in which the propelling 70 steam jet is omitted, it is desirable to heat the oil in the sight-feed as well as in the oil cup, and this is accomplished by passing the steam or hot water to the heater through the fitting L', which also contains the oil 75 10 discharge conduit from the sight-feed. The same effect is produced in the sight-feed K' on the opposite side of the cup A, and which furnishes oil to the air pump by extending the radiator tube L² into a nipple t of the 80 fitting t', forming the upper portion of the sight-feed K'. Thus, the fitting t' is supplied with heat from the steam in the radiator L² sufficient to maintain the oil at proper temperature when it is discharged 85 15 from the sight-feed K'. 20

Air brake lubricator.—It has been stated that the sight-feed K' is employed for feeding oil to the air brake steam cylinder. The amount of oil which is fed through this 90 25 sight-feed is small in comparison with that fed through the sight feed K and delivered to the locomotive cylinders, and the construction, as hereinafter described, is designed to produce a uniform feeding of this 95 30 limited quantity of oil. As shown, M is a valve for controlling the feeding of the oil from the tube d to the oil discharge nozzle M' in the sight-feed. The upper end of this sight-feed is formed by the fitting t' as before described, and the oil is discharged 100 35 therefrom into a conduit N, which connects to the conduit N' leading from the steam box H to the air brake cylinder. The conduit N' is provided with the usual valve or 105 40 throttle N². 45

With certain constructions of the lubricator, the oil fed to the air brake is propelled by a steam jet having a source of supply independent of that controlled by the throttle 50 55 valve N². The result is that when the throttle is closed, steam entering by the way of the jet will, at times, cause the continued operation of the pump. With my construction, this difficulty is avoided by dispensing with the propelling steam jet, and the feeding of the oil is effected by the following construction:—t² is a chamber formed in the fitting t' above the level of the discharge opening to the conduit N. O is a nozzle having a restricted passage O' therein and located in the nipple t⁴ to which the conduit N is connected. This nozzle will permit the feeding therethrough of a maximum quantity of oil required for the steam cylinder of the air brake, but nevertheless 60 65

forms a restriction, which prevents the free communication between the chamber t² and the conduit N. During the operation of the air pump, at each reversal of the piston there occurs a pulsation, which momentarily 70 increases the pressure of steam in the conduit N' and this increased pressure is communicated to the steam in the conduit N and thence through the restricted passage O' to the chamber t² above the sight-feed. As 75 soon as the pressure in the conduits N, N' returns to normal, the over-pressure in the chamber t² will cause the passage of steam through the restriction O', and if in the meantime one or more drops of oil have 80 been fed through the sight-feed, these will be carried with the steam into the conduit N. Condensation of the steam within the chamber t² will replenish the water in the sight-feed K', and any surplus in condensation 85 will be fed with the oil through the restriction O' at each pulsation of the steam. On the other hand, the pressure of steam within the chamber t² is constantly renewed at each pulsation, so that in 90 effect the oil is propelled by a steam current without any connection to the source of supply other than through the discharge conduit itself. 95

For lubricating the cylinder of the pump C', a conduit V is attached to the cup A, and a check valve W is arranged in this conduit. 100

X is a valve fitting connected into the steam supply conduit J' and serving to admit oil fed through the conduit V into the steam current. 105

The check valve W prevents any possibility of steam from the conduit V passing backward and into the cup A. 110

What I claim as my invention is:—

1. In a lubricator, the combination with an oil cup of a tubular heater extending into said oil cup, a conduit from a source of steam under pressure to said tubular heater, there being a restriction within said conduit, and a discharge port from said heater of greater capacity than said restriction, whereby the pressure within said heater is reduced. 115

2. In a lubricator, the combination with an oil cup of a tubular heater therein, a conduit to said heater from a source of steam under pressure, and there being a restriction in said conduit comprising a nozzle having a tapering end directed toward the source of steam, and a surrounding chamber within the conduit for the collection of sediment. 120

3. In a lubricator, the combination with an oil cup, of a tubular heater within said cup, a conduit to said heater from a source of steam under pressure, a condenser for hydrostatically feeding the oil from said cup connected to said conduit, and there being a restriction in the conduit between said con- 125 130

denser and the heater comprising a tapering nozzle having its point directed toward the source of steam and extending into the upper end of the condenser whereby sediment is dislodged from said nozzle and collected in said condenser.

5. In a lubricator, the combination with an oil cup of a tubular heater therein, a sight-feed discharge conduit from said oil cup, there being a discharge port from said heater into said discharge conduit arranged to drain into said sight-feed, a conduit to said tubular heater from a source of steam under pressure, a valve for controlling said conduit, there being a restricted passage through said valve forming a constant drainage between said steam conduit and said heater.

10. In a lubricator, the combination with an oil cup of a tubular heater therein, a condenser for hydrostatically feeding the oil from said cup, a sight-feed forming a sight-feed discharge from said cup, a drainage conduit between said tubular heater and

said sight-feed, and a detachable conduit 25 between the steam space of said condenser and said tubular heater, having a filtering restriction therein, whereby the passage of sediment to said heater is prevented.

15. In a lubricator, the combination with an oil cup, of a water tube sight feed discharge conduit therefrom, a conduit leading from said sight feed to the part to be lubricated having a pulsating steam pressure therein, there being a restriction between 35 said conduit and the upper end of said tube, a chamber above said water tube and the level of said restriction supplied with steam from said conduit, said steam forming means for propelling the oil and the water 40 of condensation thereof being used for replenishing the water in the sight feed.

In testimony whereof I affix my signature in presence of two witnesses.

ELIJAH McCLOY.
